REMOVABLE COOLING UNIT FOR HATS

Stephen J. Bachardy, Allentown, Pa.

Application January 28, 1943, Serial No. 473,813

7 Claims. (Cl. 2-7)

This invention relates to new and useful improvements in a removable cooling unit for a hat.

More particularly, the invention contemplates the construction of a unit as mentioned which is adapted to be mounted within a hat and which is associated with a conducting arrangement terminating behind the sweatband of the hat for radiating heat and keeping the brow cool.

More particularly, the invention proposes to characterize the cooling unit by a double wall vacuum container for dry ice or other refrigerant material which may evaporate or decompose into a gas, and so readily escape.

Still further the invention proposes simple and effective means for supporting the vacuum container within the hat.

An arrangement is also proposed for efficiently conducting heat from behind the sweatband to the interior of the vacuum container so that it is absorbed and neutralized.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a hat provided with a removable cooling unit constructed in accordance with this invention.

Fig. 2 is a bottom view of Fig. 1.

Fig. 3 is a fragmentary longitudinal sectional view of Fig. 1.

Fig. 4 is a perspective view of the conducting member, per se.

Fig. 5 is a longitudinal sectional view of the vacuum container of the device.

The removable cooling unit, in accordance with this invention, is intended to be used in combination with a hat 10 of any design or construction having a crown 11 and a sweatband 12. The cooling unit includes a double wall vacuum container 13 having a neck opening 14 through which dry ice or other suitable refrigerant may be placed therein. A vented stopper 15 is provided for normally closing the neck opening 14. This stopper 15 has a vent passage 16 for the escape of gas if the refrigerant is dry ice, or for the escape of other vapor substances if the refrigerant is of a different nature.

Means is provided for supporting the container 13 within said hat 10. This means comprises a strap 17 attached within the crown 11 of the hat and having a loop portion 18 through which the

container 13 is engaged. Said container is provided with a groove 19, one side 19^a of which forms wall 19^b which is arranged close to a portion 13^b of the interior wall 13^a of the container 13. The other wall 19^c of the groove of the container 13 is also arranged close to a depressed portion 13^c of the interior wall 13^a, leaving a narrow space 13'', compared with the wider spacing 13' all around, between the walls of the container 13. Through the closely spaced walls 19^b and 19^c, the cool air may efficiently radiate from the interior to the exterior of the container. A heat conducting member 20 is provided with a top portion 21 normally engaged within the groove 19, and a bottom portion 22 normally engaging behind the sweatband 12 of the hat.

The conducting member 20 is shown constructed of three sections, indicated by the numerals 23, 24 and 25. These sections may be of different materials having different conducting coefficients. For example, these sections may be of lead, copper, tin, or foil of other kinds of sheet material.

It should be noted that the closed end of the container 13 flares outwards (see Fig. 2) for a distance sufficient to extend around the brow of a person wearing the hat. The sections 23, 24 and 25 are each of a width corresponding with the width closed end of the container. With this arrangement it is possible to shift the conducting member 20 so that one of the sections or the other of the sections of the conducting member are located behind that portion of the sweatband which engages the brow.

With this invention, heat from the brow will be readily conducted and this will remove the discomfort of wearing a hat, particularly when it is warm. Most persons perspire at the brow when wearing a hat, and it is calculated that this invention will eliminate this discomfort.

The amount of spacing 13'' between the front bottom wall 13^c and the wall 19^c, above the brow of the wearer, will be experimentally determined to produce the desired temperature above the brow.

This cooling unit may be refilled with dry ice or other refrigerant, in hot days and the vacuum container may be entirely removed from the hat in normal or cool weather.

While I have illustrated and described the preferred embodiments of my invention, it is to be understood that I do not limit myself to the precise constructions herein disclosed and the right is reserved to all changes and modifications com-

ing within the scope of the invention as defined in the appended claims.

Having thus described my invention, what I claim as new, and desire to secure by United States Letters Patent is:

1. In combination with a hat, a removable cooling unit, comprising a double wall vacuum container having a neck opening through which dry ice or other refrigerant may be placed therein, a vent stopper for said neck opening, means for supporting said container within said hat, said container having an inner and outer wall evenly spaced from one another, except at a comparatively small area opposite the neck opening, where the spacing is considerably reduced for efficient heat absorption at the brow of the wearer.

2. In combination with a hat, a removable cooling unit, comprising a double wall vacuum container having a neck opening through which dry ice or other refrigerant may be placed therein, a vent stopper for said neck opening, means for supporting said container within said hat, said container having an inner and outer wall evenly spaced from one another, except at a comparatively small area opposite the neck opening, where the spacing is considerably reduced for efficient heat absorption at the brow of the wearer, said container having a grooved portion in the vicinity of the reduced spaced portion of the container, and a heat conducting member mounted in said groove projecting downwardly therefrom.

3. In combination with a hat, a removable cooling unit, comprising a double wall vacuum container having a neck opening through which dry ice or other refrigerant may be placed therein, a vent stopper for said neck opening, means for supporting said container within said hat, said container having a grooved portion one side of which forms a narrow space with the interior of said container for efficient heat absorption to the interior of said container, and a heat conducting member mounted in said groove and having a portion for extending against the inner face of the sweatband of said hat.

4. In combination with a hat, a removable cooling unit, comprising a double wall vacuum container having a neck opening through which dry ice or other refrigerant may be placed therein, a vent stopper for said neck opening, means for supporting said container within said hat, said container having a grooved portion one side of which forms a narrow space with the interior of said container for efficient heat absorption to

the interior of said container, and a heat conducting member mounted in said groove and having a portion for extending against the inner face of the sweatband of said hat, said vent stopper having a passage for the escape of gas.

5. In combination with a hat, a removable cooling unit, comprising a double wall vacuum container having a neck opening through which dry ice or other refrigerant may be placed therein, a vent stopper for said neck opening, means for supporting said container within said hat, said container having a grooved portion one side of which forms a narrow space with the interior of said container for efficient heat absorption to the interior of said container, and a heat conducting member mounted in said groove and having a portion for extending against the inner face of the sweatband of said hat, said means for supporting said container comprising a strap attached to the hat and having a loop portion engaging about the container.

6. In combination with a hat, a removable cooling unit, comprising a double wall vacuum container having a neck opening through which dry ice or other refrigerant may be placed therein, a vent stopper for said neck opening, means for supporting said container within said hat, said container having a grooved portion one side of which forms a narrow space with the interior of said container for efficient heat absorption to the interior of said container, and a heat conducting member mounted in said groove and having a portion for extending against the inner face of the sweatband of said hat, said means for supporting said container comprising a strap attached to the hat and having a loop portion engaging about the container.

7. In combination with a hat, a removable cooling unit, comprising a double wall vacuum container having a neck opening through which dry ice or other refrigerant may be placed therein, a vent stopper for said neck opening, means for supporting said container within said hat, said container having a grooved portion one side of which forms a narrow space with the interior of said container for efficient heat absorption to the interior of said container, and a heat conducting member mounted in said groove and having a portion for extending against the inner face of the sweatband of said hat, comprising a top portion engaging the groove and a bottom portion engaging behind said sweatband.
